(57) **CLAIM**

The ornamental design for a cat scratcher, as shown and described.

DESCRIPTION

FIG. 1 is a perspective view of a cat scratcher showing my new design;

FIG. 2 is a left side view of FIG. 1;

FIG. 3 is a right side view of FIG. 1;

FIG. 4 is a top plan view of FIG. 1;

FIG. 5 is a bottom plan view of FIG. 1;

FIG. 6 is a rear view of FIG. 1;

FIG. 7 is a front view of FIG. 1;

FIG. 8 is an exploded perspective view thereof;

FIG. 9 is a perspective view of the vertical segment shown in FIG. 1; ps FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9;

FIG. 16 is a top plan view of the horizontal segment shown in FIG. 8;

FIG. 17 is a bottom plan view of FIG. 16;

FIG. 18 is a right side view of FIG. 16;

FIG. 19 is a left side view of FIG. 16;

FIG. 20 is a front view of FIG. 16;

FIG. 21 is a rear view of FIG. 16;

FIG. 22 is a top plan view of the insert shown in FIG. 8;

FIG. 23 is a bottom plan view of FIG. 22;

FIG. 24 is a right side view of FIG. 22;

FIG. 25 is a left side view of FIG. 22;

FIG. 26 is a front view of FIG. 22; and,

FIG. 27 is a rear view of FIG. 22.
